US00D959838S

(12) **United States Design Patent** (10) **Patent No.:** **US D959,838 S**
Martell (45) **Date of Patent:** **** Aug. 9, 2022**

(54) **APPAREL POCKET FOR GOLF BAG**

5,597,144 A 1/1997 Lee
5,634,616 A 6/1997 Wang et al.
5,799,786 A 9/1998 Beck et al.
5,816,544 A 10/1998 Hsieh
5,823,485 A 10/1998 Park
5,954,255 A * 9/1999 Beebe A63B 55/00
224/645

(71) Applicant: **KARSTEN MANUFACTURING CORPORATION**, Phoenix, AZ (US)

6,220,433 B1 4/2001 Kang
6,296,117 B1 10/2001 Chen
6,311,836 B1 11/2001 Maeng
6,382,572 B1 5/2002 Lin
6,386,362 B1 5/2002 Cheng
6,390,295 B2 5/2002 Rhee
6,481,674 B1 11/2002 Lin

(72) Inventor: **James D. Martell**, Phoenix, AZ (US)

(Continued)

(73) Assignee: **Karsten Manufacturing Corporation**, Phoenix, AZ (US)

(**) Term: **15 Years**

(21) Appl. No.: **29/705,715**

(22) Filed: **Sep. 13, 2019**

FOREIGN PATENT DOCUMENTS

FIG. 1 is a first perspective view of an apparel pocket for golf bag;

U.S. PATENT DOCUMENTS

FIG. 2 is a second perspective view thereof;

4,226,389 A 10/1980 Neth
4,778,136 A 10/1988 Reimers
4,834,235 A 5/1989 Solheim et al.
4,898,352 A 2/1990 Hoffman
1,438,311 A 12/1992 Kerlogue
5,178,273 A 1/1993 Igarashi
5,339,951 A 8/1994 Chen
5,351,921 A 10/1994 Chen
5,356,003 A 10/1994 Gretz et al.
5,407,155 A 4/1995 Chung
5,415,285 A 5/1995 Reimers

FIG. 3 is a first side view thereof;

FIG. 4 is a second side view thereof;

FIG. 5 is a front view thereof;

FIG. 6 is a rear view thereof;

FIG. 7 is a top view thereof; and,

FIG. 8 is a bottom view thereof.

The broken lines showing portions of a golf bag illustrate environmental structure and forms no part of the claimed design.

1 Claim, 8 Drawing Sheets
